DESIGN FOR A DEFENSE STAMP VENDING DEVICE OR SIMILAR ARTICLE

Charles A. Byrnes, Chicago, Ill.

Application January 2, 1942, Serial No. 104,976

Term of patent 7 years

To all whom it may concern:

Be it known that I, Charles A. Byrnes, a citizen of the United States, residing at Chicago, in the county of Cook and State of Illinois, have invented a new, original, and ornamental Design for a Defense Stamp Vending Device or Similar Article, of which the following is a specification, reference being had to the accompanying drawing, forming part thereof, and wherein:

Fig. 1 is a perspective view of a defense stamp vending device, showing my new design; and

Fig. 2 is a top plan view thereof on a reduced scale.

Portions of the design are lined to indicate coloring.

I claim:

The ornamental design for a defense stamp vending device or similar article, as shown and described.

CHARLES A. BYRNES.
